UNITED STATES PATENT OFFICE.

RICHARD HOLLUNDER, OF WHITE PLAINS, NEW YORK.

NECKTIE FASTENING.

Application filed July 24, 1926. Serial No. 124,709.

This invention relates to improvements in neckties, particularly in the means for holding such ties on the collars, and it is the principal object of my invention to provide 5 a holder or hanger for neckties of the so-called ready-made type, either bows or elongated ties, allowing a ready attachment to a collar, ensuring a firm hold on the same and a convenient and quick removal therefrom.

Another object of my invention is to provide a necktie holder or hanger of novel and improved, extremely simple and inexpensive construction, detracting nothing 15 from the pleasing appearance of the tie, yet being durable and efficient, as well as positive in its operation.

A further object of the invention is the provision of a necktie holder or hanger 20 equipped with a clamping means for allowing a convenient operation of the attachment and detachment of the ties by this means.

A still further object of the invention is 25 the provision of a necktie holder or hanger which may readily be attached to any make of necktie of the ready-made bow or hanger type now on the market without necessitating vital and expensive changes, and which 30 may equally well be used for the attachment of such neckties to stiff, semi-soft and soft collars.

The necktie holder or hanger according 35 to my invention allows furthermore, a securing of the tie independently of the collar button and to collars of any height, as the clamp thereof firmly grips over the upper edges of the overlapping collar flaps, and thus, by gripping both flaps gives an additional hold to the same ensuring at all times 40 a good and orderly appearance. Another advantage of my improved necktie holder and hanger is to be seen in the fact that it presses the side wings customarily used with 45 ready-made ties, snugly against the upper inner collar edge and ensures thus at all times a pleasing appearance and uniform fit for the ties on the collars.

These and other objects and advantages 50 of my invention will become more fully apparent as the description thereof proceeds, and will then be more specifically defined in the appended claims.

In the accompanying drawing, forming a 55 material part of this disclosure:

Fig. 1 is a perspective view of a necktie

of the bow type equipped with a holder or hanger constructed according to my invention.

Fig. 2 is a cross-section on line 2—2 of 60 Figure 1.

Fig. 3 is a detail view of the necktie-holder per se.

Fig. 4 is a rear view of a necktie of the 65 elongated hanger type equipped with a holder or hanger constructed according to my invention.

The necktie-holder or hanger constructed 70 according to my invention, as illustrated on the drawings, comprises a base or body plate 10 having a tongue or lip 11 formed therewith and bent out of the plane of the plate 10, as indicated at 12.

The upper edge of the plate, to both sides 75 of the tongue 11 is formed as spring hinge-members 13 and 14, to the common pintle, of which, 15, between the members 13 and 14, a stem 16 is secured, having a wing 17 formed at its outer end, while a wart 18 engages the tongue 11 to press the same forward or release the tongue, as the case may be, if the necktie is to be attached to a collar or removed therefrom. At the rear of the necktie, the wing 17 has a rounded protuberance 80 or lip 19 or the like formed therewith, to allow a gripping by the fingers in order to 85 facilitate the operation of the holder-wing.

The holder plate is secured to the necktie 90 fabric at the rear thereof, as indicated for instance at 20, so that it cannot be observed 95 from the front, and preferably somewhat below the upper edge of the necktie, so that it cannot be observed from the front and presses against the customary necktie wing 21 of the tie 22.

In Figure 4 I have illustrated the application 95 of my improved necktie holder and hanger to a tie of the ready-made type and elongated hanger construction. The construction of the holder shown in this figure 100 is generally the same as that described with respect to the bow type.

The operation of my device will be entirely clear from the above description. The plate 10 is securely fastened to the tie by 105 sewing etc. so that it is not visible from the front thereof. If it is now desired to secure the necktie in position on a collar, the wing part 17 or the holder is turned around its hinges to engage behind the collar so that 110 its bent part 16 will tightly grip over the upper overlapping collar edges and hold the

parts firmly together. A removal of the tie is readily effected by simply gripping the lip 19 with the finger and turning the wing part 17 of the holder towards the front to disengage part 16 from the upper collar edges.

It is to be understood, that while I have shown and described the preferred form of my invention as one example of the many ways in which the same may be practically constructed, such changes as come within the scope of the appended claims may be made in the general construction and in the minor details of the invention without departure from the gist thereof.

Having thus described my invention, what I claim as new and desire to secure by Letters Patent is:

1. Necktie holder or hanger comprising a base, a tongue stamped from the material of said base and projecting out of the plane thereof, a means hinged to said base and adapted to grip over the upper edge of a collar, and a means for facilitating its removal therefrom.

2. Necktie holder or hanger comprising a base adapted to be attached to said base invisibly, a tongue formed with said base and bent at its upper end out of the plane thereof, hinges formed at the upper edge of said plate, a clamping member attached to said hinges and adapted to grip over the upper collar edges, and a means for facilitating its disengagement therefrom.

3. Necktie holder or hanger for ties of the ready-to-wear type comprising a base secured to the material of the tie invisible from the front, a tongue vertically formed from the material of the base, the upper edge of said tongue bent out of the plane of said base, a wing, a stem connecting said wing to said base, a wart on said stem engaging said tongue, hinges for connecting said stem to said base, and a projection on the central upper edge of said wing to facilitate the removal of the tie from a collar.

Signed at New York in the county of New York and State of New York this 17th day of June A. D. 1926.

RICHARD HOLLUNDER.
